UNITED STATES PATENT OFFICE.

PIERRE PLANTINGA, OF CLEVELAND, OHIO.

APPARATUS FOR MANUFACTURING GAS.

1,122,634.

Specification of Letters Patent. Patented Dec. 29, 1914.

Application filed December 20, 1909. Serial No. 533,980.

To all whom it may concern:

Be it known that I, PIERRE PLANTINGA, a citizen of the United States, resident of Cleveland, county of Cuyahoga, and State of Ohio, have invented a new and useful Improvement in Apparatus for Manufacturing Gas, of which the following is a specification, the principle of the invention being herein explained and the best mode in which 10 I have contemplated applying that principle, so as to distinguish it from other inventions.

My invention relates to apparatus used in the manufacture of gas, and particularly to 15 producers for manufacturing semi-water-gas.

The object of the invention is to increase the economy of production of such semi-water-gas, and particularly with reference 20 to the continued production of a uniform quality of such gas.

The said invention consists of means hereinafter fully described and particularly set forth in the claims.

25 The annexed drawing and the following description set forth in detail certain means for carrying out my invention, the disclosed, means, however, constituting but one of various mechanical forms in which the principle 30 of the invention may be applied.

In said annexed drawings:—Figure 1 represents diagrammatically an apparatus embodying my invention, Fig. 2 is a detail of a modification, and Fig. 3 is a diagrammatic 35 illustration of a modified form of my invention.

The apparatus illustrated in the drawing, and to which my invention may be applied, includes a producer A of any approved 40 form, a scrubber B connected in the usual manner with said producer, and the usual means, consisting of a suitable exhauster, (not shown), conduits and openings by means of which a current of air may be 45 caused to enter the producer, at a, the required gas formed in the latter, drawn through the scrubber B, withdrawn from the latter at b into the duct C and through the subsequent portions of the gas-making 50 apparatus which are connected with the aforementioned exhauster.

The apparatus as thus far described, is old and well-known, and when operating without any further modification, air and 55 steam are simultaneously blown into the

producer, where they come in contact with the fuel, the resulting product being what is ordinarily known as semi-water-gas. This gas is withdrawn from the producer by the exhauster, the latter creating the necessary 60 suction for the introduction of the required air into the producer. Under these conditions, the introduction of the steam is more or less independent of the introduction of the air, and a variation in the amount of air 65 resulting from a change of conditions such as would produce a greater or less suction of air, and therefore a greater or less quantity of air passing through the producer, would not affect materially the quantity of steam 70 introduced. As a result, the relative proportions of air and steam would vary, and the character of the semi-water-gas made would also vary. To overcome this variation in the character of the gas produced, I 75 introduce at a point beyond the producer, and in an outlet duct, means for automatically regulating the introduction of steam so as to maintain a definite predetermined relationship between the rate of flow of gas 80 produced and flowing through such duct, and the amount of steam introduced into the producer: said means being adapted to vary the rate of the flow of the steam directly as the variation of the rate of flow of the produced gas through said duct, thus maintaining 85 conditions such as will cause a continued production of a gas of uniform character. This means further that an increased production of gas must be coincident with an 90 increase in the introduction of air into the producer and likewise with an increase in the consumption of fuel. To accomplish this result, I provide an adjutage F, which 95 may be located in any convenient part of the apparatus and in the path of the produced gas. As shown in Fig. 1, this adjutage is located in the duct C, and consists preferably of a Venturi-tube. This adjutage is connected by means of the two pipes f f, with a 100 pressure-operated device G, said device including a diaphragm g, which is operated as a result of the difference in pressure created in the Venturi-tube. This diaphragm is connected with a valve H, located in the steam pipe E, and this part of the apparatus is arranged so that a reduced rate of flow of gas through the adjutage will impart to the steam valve a closing movement. It will 105 therefore be seen that as the rate of flow of 110

the gas increases or decreases in the duct C, the amount of steam introduced into the producer will correspondingly increase or decrease, and a constant relation of the amount of steam and air introduced into the producer thus maintained.

Instead of a Venturi-tube, an ordinary baffle-plate J may be introduced in the path of travel of the gas, as illustrated in Fig. 2, 10 and this baffle-plate may be provided with a pointer j and graduated arc j', whereby the position of the baffle-plate may be determined, the said plate being mounted so that it may be set in different fixed positions, as will be readily understood.

In Fig. 3 I have illustrated a modified form of apparatus embodying my invention, which varies from that above described in that instead of controlling the flow of 20 steam directly by means of the valve H, said valve is arranged to control the flow of water through a pipe K, which feeds a flash-boiler L. This boiler supplies the steam to the producer A. By means of this construction, an increase or decrease in the flow 25 of gas through the pipe C will increase or decrease the amount of water supplied to the boiler, and hence increase or decrease the amount of steam supplied to the producer.

Having thus fully described my invention, what I claim and desire to secure by Letters Patent is:

1. In an apparatus for the manufacture 35 of gas, the combination of a gas producer; means for introducing steam into the latter; means for introducing air into said producer; and means controlled entirely by the velocity of the gaseous current after leaving 40 the producer, for maintaining a definite relationship between the rate of flow of the

gas produced and the rate of flow of steam into the producer.

2. In apparatus for the manufacture of 45 gas, the combination of a gas producer; means for introducing steam into the latter; means for introducing air into said producer; and means interposed in the path of movement of the gas after leaving the producer and actuated by the flow of the gas 50 passing it, for maintaining a definite relationship between the rate of flow of the gas produced and the rate of the flow of steam into the producer.

3. In an apparatus for the manufacture 55 of gas, the combination of a gas producer; means for introducing steam into the latter; means for introducing air into said producer; and means interposed in the path of the gas after leaving the producer for creating a differential pressure; and means for controlling the steam supply and controlled 60 by said differential pressure-means.

4. In an apparatus for the manufacture 65 of gas, the combination of a gas producer; means for introducing steam into the latter; means for introducing air into said producer and an adjutage interposed in the path of movement of the gas after leaving 70 said producer; a pressure-operated device connected with said adjutage and controlled by the difference of pressure created by the latter; and a valve controlling the flow of steam into the producer and connected with said pressure controlled device.

Signed by me, this 18th day of December, 1909.

PIERRE PLANTINGA.
